UNITED STATES PATENT OFFICE.

JAMES R. THOMAS, OF LEXINGTON, TENNESSEE.

SLING-SHOT GUN.

1,235,398.

Specification of Letters Patent. Patented July 31, 1917.

Application filed February 14, 1917. Serial No. 148,573.

To all whom it may concern:

Be it known that I, JAMES R. THOMAS, a citizen of the United States, residing at Lexington, in the county of Henderson and 5 State of Tennessee, have invented certain new and useful Improvements in Sling-Shot Guns, of which the following is a specification, reference being had to the accompanying drawings.

10 This invention relates to missile projectors and particularly to a gun in the nature of a sling-shot.

The general object of my invention is to provide a very simple missile projector having the general form of a gun that is provided with a stock, a trigger and a forwardly projecting extension from the stock which has the similitude of or is analogous to a barrel, in which the projectile is 20 projected by a projectile carrier urged to its forward position by contractile rubber bands or like means.

Another object of the invention is to provide a very simple construction of this 25 character which may be readily made out of heavy wire and which is, therefore, very cheaply constructed and may be put upon the market at a small cost.

A further object is to improve upon the 30 details of construction of devices of this character.

Other objects will appear in the course of the following description.

My invention as illustrated in the accompanying drawing, in which—

Figure 1 is a side elevation of a toy gun constructed in accordance with my invention;

40 Fig. 2 is a section on the line 2—2 of Fig. 1;

Fig. 3 is a section on the line 3—3 of Fig. 1;

Fig. 4 is a section on the line 4—4 of Fig. 1;

45 Fig. 5 is a section on the line 5—5 of Fig. 1;

Fig. 6 is a fragmentary section on the line 6—6 of Fig. 1.

Referring to these figures, it will be seen 50 that my improved gun, as it may be termed, comprises a stock or shoulder piece designated generally 10 and which may be formed in any desired manner but is illustrated as formed of a wire 11 bent to take 55 the outline of the usual stock. The extremities of the wire 11 are operatively con-

nected to a body 12 which corresponds to the ordinary breech portion of the gun. This body 12 is preferably formed of a casting having sockets for the reception of the ends of the wire 11, the wire being held 60 in these sockets by means of the screws 13. Sockets are also provided for forwardly extending tubular members 14 which are screw-threaded into the body. The body upon one face is cut away as at 16 to form a 65 housing for a trigger 17, this recess 16 being formed with a contracted neck 18 opening at the forward end of the body. Pivot- 70 ed within this recess 16, as by means of the screw 19 is the trigger 17 which has a downwardly extending finger portion 20 which extends down below the body and this trigger is also provided with the forwardly extending detent 21 having a hooked end, this portion 21 being disposed within 75 the neck 18. Below the lower end of the trigger is the trigger guard 22, attached to the body 12 in any suitable manner. The body is closed by a plate 15.

Rigidly connected to the outer ends of 80 the tubular members 14 are sleeves 23, held in place by set screws 24, and integrally or otherwise connected to these sleeves is a cross bar 25 having rearwardly projecting brackets 26 between which brackets is 85 mounted a spindle 27. This pin or spindle 27 is detachable from the brackets. Slidably mounted upon the tubular members 14, which constitute guides, are the sleeves 28 and 29 which are carried by a cross piece 30, 90 the forward edge of which is formed with brackets 31 connected by a removable pin 32 or spindle. The rear edge of the cross bar 30 is formed with a rearwardly projecting hook-shaped detent 33 adapted to 95 engage with the forwardly extending bill of the detent 21 when the cross bar is retracted to its full extent. The bar 30 is extended beyond the sleeve 29 and is forwardly bent as at 34 and is provided with a small seat 100 35 for the reception of the shot or other projectile. The shot is held in place by means of a very light spring 36 in this recess. The forward upwardly extending portion 34 of the cross bar 30 is provided with a 105 sight 37, and the pins or spindles 27 and 32 extend through opposite ends of an elastic band 38.

Surrounding the tubular guide members 14 are the coil springs 39. These are com- 110 pression springs and at their rear ends bear

against rubber buffers 40 slidably mounted upon the tubular members 14. Engaging in the tubular members 14 are the ends of a wire 41 which constitutes an extension on the gun and suggests the barrel of the gun. The length of wire is bent to outline this barrel and the ends of the wire inserted telescopically within the tubular members 14 and held in place therein by set screws 10 42 or other suitable means.

In practical use a projectile is placed within the seat 35 and the cross bar 30 retracted against the force of the rubber band 38 until the trigger detent is engaged with 15 the detent 33. Then when it is desired to fire the gun, the trigger 20 is pulled, releasing the detents, the rubber band urges the cross bar 30 forward and the force is such as to project the projectile from its 20 seat, the relatively weak spring 36 shifting under the momentum of the projectile so as to permit the projectile to pass.

While I have illustrated certain details of construction, I wish it understood that 25 I may vary these details in many ways without departing from the spirit of the invention. The construction illustrated, however, permits the gun to be very cheaply manufactured and permits the parts to be 30 readily assembled. It also permits the rubber band 38 to be renewed from time to time. While I have illustrated one rubber band 38, it will be understood that a plurality of small rubber bands might be used 35 instead. The compression springs 39 receive the impact of the forwardly moving cross bar 30, which may be termed an ejector, and this sudden stoppage of the movement of this ejector or cross bar 30 will 40 cause the projectile to fly out of its seat in the line of its movement. Neither do I wish to be limited to the particular impact receiving means or doubles which I have illustrated as these might be modified without 45 departing from my invention.

Having described my invention, what I claim is:

1. A gun of the character described comprising a breech member having a recess 50 on one face, the recess opening upon the forward end of the breech member and upon the lower edge thereof, a trigger pivoted in said recess and having a forwardly extending detent, a cover plate extending over 55 the recess in the breech member, a stock member comprising a rod bent into the general similitude of a gun stock, the ends of the rod being operatively engaged with the breech member, vertically spaced guides 60 extending forward from the breech member, a cross bar sliding upon said guides and constituting an ejector and having an inwardly extending detent engageable with the detent on the trigger and also formed 65 with a projectile seat, and resilient means

urging the ejector away from the breech member when the trigger is released.

2. A gun of the character described comprising a breech member recessed on one face, the recess opening upon the forward end of the breech member and upon the lower end thereof, a trigger pivoted in said recess and having a forwardly extending detent, a stock member attached to the rearward end of the breech member, forwardly 70 extending guides comprising rods engaged in the breech member, the rods being disposed in vertical alinement, a cross bar slidably mounted upon the guides and constituting an ejector and having an inwardly 75 extending detent engageable with the detent on the trigger, and resilient means for urging the ejector away from the breech member.

3. A gun of the character described comprising a breech member formed with a recess opening upon the lower edge of the breech member and upon the forward edge thereof, a trigger pivoted in the recess and having a forwardly extending detent, a stock member attached to the breech member, forwardly extending tubular rods mounted upon the breech member and disposed in vertical alinement, and a barrel member formed of a rod bent into the outline of a gun stock and having its rear ends disposed within the tubular members, a cross bar mounted upon the tubular members for sliding movement and having a detent engageable by the detent on the trigger and formed with a projectile seat, said cross bar constituting an ejector, and resilient means urging the ejector away from the breech member.

4. A gun of the character described comprising a breech member having a trigger mounted thereon, the trigger being formed with a detent, a stock member composed of a rod bent into the outline of a gun stock and having its ends detachably engaged with the breech member, forwardly extending rods having their rear ends detachably engaged with the breech member and disposed in vertical relation, a rigid cross bar detachably engaged with the forward ends 115 of said rods, a cross bar slidably engaged with the rods rearward of the first named cross bar and constituting an ejector, said cross bar being formed with a projectile seat, the cross bar having a detent engageable 120 with the trigger detent, and an elastic element operatively connected between the first named cross bar and the ejector and urging the latter forward.

5. A gun of the character described comprising a stock member, a breech member to which the stock member is engaged and having a recess on one face, the recess opening upon the forward end of the breech member and upon the lower edge thereof, a trigger 125

2
pivoted in said recess and having a forwardly extending detent, vertically spaced guides extending forward from the breech member, a cross bar having sleeves embracing said guides and rigidly held thereon, a cross bar having sleeves slidably engaging the rear ends of the guides and constituting an ejector, said ejector having an inwardly extending detent engageable with the detent 10 on the trigger and having an upwardly and forwardly extending portion formed with a forwardly opening projectile seat, a resilient contractile element operatively engaging the forward cross bar and the ejector 15 and urging the latter to a forward position, coil springs surrounding the guides and bearing at their rear ends against the forward cross bar, and buffer members slidably mounted on the guides at the rear ends of 20 the springs and receiving the impact of the sleeves of the ejector cross bar.

6. A gun of the character described comprising a stock member, a breech member to which the stock member is engaged and having a recess on one face, the recess opening upon the forward end of the breech member 25 and upon the lower edge thereof, a trigger pivoted in said recess and having a forwardly extending detent, vertically spaced

guides extending forward from the breech member, a cross bar having sleeves embracing said guides and rigidly held thereon, a cross bar having sleeves slidably engaging the rear ends of the guides and constituting an ejector, said ejector having an inwardly 30 extending detent engageable with the detent on the trigger and having an upwardly and forwardly extending portion formed with a forwardly opening projectile seat, a resilient contractile element operatively engaging the 35 forward cross bar and the ejector and urging the latter to a formed position, coil springs surrounding the guides and bearing at their rear ends against the forward cross bar, buffer members slidably mounted on the 40 guides at the rear ends of the springs and receiving the impact of the sleeves of the ejector cross bar, and a barrel portion composed of a length of wire bent to the outline 45 of the barrel and having its ends detachably 50 engaged in the forward ends of the tubular guides.

In testimony whereof I hereunto affix my signature in the presence of two witnesses.

JAMES R. THOMAS.
